UNITED STATES PATENT OFFICE.

CHARLES H. McCANN, OF CLEVELAND, OHIO.

DRAFT-GEAR-SUPPORTING MEANS.

1,249,792.

Specification of Letters Patent. Patented Dec. 11, 1917.

Application filed July 10, 1916. Serial No. 108,311.

To all whom it may concern:

Be it known that I, CHARLES H. McCANN, a citizen of the United States, residing at Cleveland, in the county of Cuyahoga and State of Ohio, have invented certain new and useful Improvements in Draft-Gear-Supporting Means, of which the following is a specification.

The invention relates to improved means for supporting draft gears and the couplers at the forward ends thereof. The invention has for its primary objects; the provision of improved means for supporting the draft gear proper, wherein the construction is simplified and cheapened, and arranged so that the gear may be readily removed; and the provision of an improved coupler support or carry iron, which is easily removed or released, but which is securely guarded against accidental displacement. Certain embodiments of the invention are illustrated in the accompanying drawings, wherein—

Figure 1 is a vertical section through a draft gear construction involving my invention, such section being taken intermediate the draft sills of a car; and Figs. 2 and 3 are sections on the lines II—II and III—III respectively, of Fig. 1.

Referring first to the construction of Figs. 1, 2, and 3, the reference numerals 1 and 2 represent the center sills of a car, and 3 and 4 (Fig. 3) are draft casing members rigidly secured to the sills by means of the rivets 5 (Fig. 1), a portion only of which are shown, such members being castings and commonly referred to as the draft castings. Supported between the draft castings is the draft gear, which comprises the usual spring pocket 6, the springs 7 and 8, and the follower plates 9 and 10.

Projecting downwardly from the lower sides of the draft castings 3 and 4 and integral therewith, are the lugs 11 and 12. These lugs serve to carry the supporting bar 13, which supporting bar has one end turned down, as indicated at 14, and is provided at the other end with a cotter 15 to prevent the accidental removal of the bar. This is an advantageous method of supporting the draft gear since the lugs 11 and 12 can be formed as a part of the castings without additional expense, and the use of the bar 13 permits of the ready assembling and disas-

sembling of the apparatus. This arrangement avoids the necessity of providing the draft sills 1 and 2 with separate supporting means or of perforating the sills to provide for a supporting means for the draft gear.

Secured to the forward end of the gear is the coupler 16 having the shank 17. This shank 17 extends through an opening in the striking plate 18, as indicated in Fig. 2, the striking plate being secured to the draft sills in any desired manner. The opposite sides of the striking plate are provided with sockets and upright stops 19 and 20, the said sockets serving to receive the ends of the supporting bar 21, while the stops prevent the endwise movement of such bar. The bar or carry iron 21 extends beneath the shank 17 of the coupler, and is perforated at one end, preferably the right-hand end, as indicated in Fig. 2. The striking plate is correspondingly perforated, and a cotter 22 extends through the perforations. This serves as an additional guard against the accidental removal of the bar, although there is little strain or wear upon this cotter because of the shoulders 19 and 20 which normally prevent the bar from moving in an endwise direction. The bar may be readily removed by taking out the cotter pin, tilting the bar upward at its left-hand end, and then sliding it endwise, as indicated in the dot-and-dash lines at 23.

What I claim is:

1. In combination with a pair of sills, a draft member rigidly secured to the inner face of each sill and provided with perforated lugs extending below the lower edges of the sills, and a supporting bar for the draft gear extending through the perforations entirely below the center sills and removable laterally beneath one of the center sills.

2. In combination with a pair of sills, a draft member rigidly secured to the inner face of each sill and provided with perforated lugs extending below the lower edges of the sills, one of said lugs also extending laterally beneath the adjacent sill, a supporting bar extending through the said lugs and securing means for the bar at the end thereof having the laterally extending end.

CHARLES H. McCANN.
